UNITED STATES PATENT OFFICE.

ALBERT HOLMES, OF PETALUMA, CALIFORNIA.

LIFE-BOAT.

SPECIFICATION forming part of Letters Patent No. 248,097, dated October 11, 1881.

Application filed July 5, 1881. (No model.)

To all whom it may concern:

Be it known that I, ALBERT HOLMES, a citizen of the United States, and residing at Petaluma, in the county of Sonoma and State 5 of California, have invented certain new and useful Improvements in the Construction of Life-Boats, of which the following is a specification.

The object of my invention is, first, to provide a life-boat in which the requisite buoyancy is obtained by means of alternating layers or bands of air-tight metal tubing and cork; second, to provide a life-boat which may be constructed from any ordinary boat by simply attaching to it the air-tight metal tubes and the alternating layers of cork. These objects I accomplish by means of the mechanism illustrated in the accompanying drawings, in which—

20 Figure 1 is a plan view, Fig. 2 is a side elevation, and Fig. 3 is a cross-section.

Similar letters of reference are used to indicate like parts throughout the several views.

To the top of the gunwale I secure, by means 25 of bolts, screws, or strap-irons, the air-tight hollow tube A. This tube is divided into lengths a a, and between these lengths I place the rowlocks b, which are attached to the gunwale in the ordinary manner.

30 Upon the inside of the boat-frame, and a short distance below the top edge thereof, I secure the air-tight metal tubes B B. These tubes extend along the port and starboard sides, in which position they are securely held 35 by any well-known means.

Upon the outside of the boat, a short distance below the top edge thereof, I attach the air-tight metal tube C, which encompasses the vessel upon all sides.

Between the tubes A and B, I place a band 40 or fillet of cork, D, and between the tubes A and C the fillet of cork E, and underneath the tube C, and attached to the side framing of the boat, the fillet of cork F. These alternate layers, bands, or fillets of cork serve the double purpose of increasing the buoyancy of the boat, and also of protecting the metal tubes from injury. I also provide metallic air-tight 45 seats or thwarts c, constructed in the form shown, and which are removable, and in themselves form efficient life-preservers. 50

Having thus described my invention, what I claim, and desire to secure by Letters Patent, is—

In a life-boat, the combination and arrangement of the air-tight metal tubes A B C, secured upon the inner and the outer sides of the boat-frame in a horizontal manner, and alternating with horizontal layers or fillets of cork, D E F, all when constructed and arranged 55 substantially in the manner as herein set forth and specified.

In testimony that I claim the foregoing I have hereunto set my hand and seal this 13th day of June, 1881.

ALBERT HOLMES. [L. S.]
